BAG

True M. Avery, Glens Falls, N. Y., assignor to
 Union Bag & Paper Corporation, Hudson Falls,
 N. Y., a corporation of New Jersey

Application March 11, 1940, Serial No. 323,439

2 Claims. (Cl. 229—70)

The present invention relates to bags and similar containers for enclosing and the mailing or transmission of articles of different kinds, and a more particular object of the invention is to provide a bag which is especially adapted for use in the camera film developing industry to facilitate the mailing or other transmission of a roll of exposed photographic film to an establishment for developing and the returning of the developed negatives and prints to the sender.

The bag according to the present invention, which may be furnished to the purchaser of a roll of film, is of a size and shape to receive the roll of film after it has been exposed in a camera, it having means, preferably a tie, for closing its mouth after insertion of the roll, and the bag preferably bears the printed address of the establishment which is to develop the film, so that it is only necessary to close the bag, affix the proper postage and deposit the bag in the mail. The bag is provided with a flap or extension to receive the return address of the sender, and this flap or extension is employed in returning the negatives developed from the film and the pictures printed therefrom, preferably by detaching it from the bag and stapling or otherwise affixing it to one end of the roll of film to be developed for identification purposes, after which it may be used to supply the return address of the sender, as by affixing it to an envelope such as usually employed in mailing or otherwise delivering negatives and prints, for which purpose the flap or extensions may be gummed on the reverse side when placed on the return envelope or package to form a sticker or address label.

The preferred form of a film roll bag according to the present invention is shown in the accompanying drawing wherein:

Figure 1 is an elevation, partly broken away, of a bag made in accordance with the present invention, the bag being shown empty but in partly expanded condition;

Figure 2 is an elevation of the opposite side of the bag shown in Fig. 1;

Figure 3 is a perspective view of the bag containing a roll of camera film, the bag being closed to form a package ready for mailing or other transmission;

Figure 4 is an end view of the closed and filled bag as viewed from the right in Fig. 3; and

Figure 5 is a detail perspective view of a part of the mouth end of the bag.

Similar parts are designated by the same reference characters in the several figures.

The bag, which is composed preferably of

paper of suitable flexibility and strength, may be of different types such as the well known "flat" or envelope type, although it is preferably of the well known "square" type made from a strip of paper formed into a tube, having opposed flat sides 1 and 2 and infolded tucks or pleats 3 and 4 which form a collapsible or bellows-like body, and a bottom 5 formed by folding and pasting a flattened end of the tube against a side of the bag. The bag is of a size and shape to receive photographic camera film rolls of the usual range of sizes when used for such purpose, and it may be made with speed and facility on a bag machine of the type commonly employed in the making of "square" or other types of bags. The mouth of the bag is provided with means for closing it, the closing means comprising preferably a tie composed of a strip 6 of tin or other soft sheet metal or other suitable pliable material which is readily bendable and capable of retaining its bent form. This tie strip is attached to the bag adjacent to its mouth by a tab 7 of paper or other suitable flexible material which is applied and secured by adhesive to one side, preferably the side 2 of the bag below its mouth, a portion of this tab extending beyond the bag mouth and being rolled about the tie strip as indicated at 8 and secured thereto as by an adhesive and milled indentations as indicated at 9. The tie strip is thus attached to and secured to the bag beyond its mouth so that it lies substantially in the plane of the side of the bag to which it is attached, and its bendable ends project beyond the edges of the bag when the bag is in its flat or collapsed form prior to its use, substantially as shown in Figs. 1 and 2.

One of the flat sides of the bag, as the side 1 thereof, preferably has printed thereon or otherwise applied thereto the address 10 of the establishment from which the roll of film was purchased or an establishment which develops films, and this side of the bag also preferably has a space 11 thereon to receive a postage stamp. A flap 12 extends from the bag, preferably from a longitudinal edge of one of its flat sides, as the side 2 as shown, this flap or extension being provided with a form or space 13 to receive the return address of the sender. The flap or extension 12 is foldable flatwise against the side 2 of the bag so that it will not catch upon other objects and be torn from the bag during handling and the form or space 13 for the sender's return address is preferably on that side of the flap or extension 12 which will lie against the side 2 of the bag when said flap or extension is

folded, thereby covering the sender's return address while the bag is being sent through the mail to the address 10, and thus avoiding possible confusion of the addresses during transmission. The flap or extension 12 may be attached to the bag in different ways, but it is preferably formed as an integral continuation of the side 2 of the bag, as by extending the outer edge of the longitudinal seam 14 which is located at the flat side 2 adjacent to the respective longitudinal edge of the bag, this seam uniting the edges of the strip from which the bag tube is made during the manufacture of the bag. The flap 12 is creased along the longitudinal edge of the side 2 of the bag, as indicated at 15, so that it may be readily folded flat, or substantially so, against that side of the bag, and may be easily torn or detached from the bag.

The flap 12, after it has been detached from the bag, may be stapled or otherwise affixed to one end of the roll of film prior to its development in order to identify the sender thereof, and after the film has been developed, it may be used to supply the address of the sender to whom the developed negatives and prints are to be returned, as, for example, by applying an adhesive to the back of this flap and affixing it to the envelope or package in which the developed negatives and prints are enclosed.

The bag as manufactured and prior to use, is collapsible into flat form substantially as shown in Fig. 1, the tie strip being straight and its ends projecting from the opposite sides of the bag mouth. The bags may therefore be stacked compactly for storage and shipment. When the bag is to be used, it is opened by expanding it, the roll of film is inserted endwise therein, and the mouth of the bag is closed and secured in closed condition by rolling the tie strip on one side down two or three times over the opposite side of the bag adjacent to its mouth end, after which the ends of the tie strip are bent around the edges and against the opposite side of the bag, as shown in Fig. 3.

Bags provided by the present invention are especially adapted for mailing rolls of exposed camera film to establishments for development. A supply of these bags may be kept on hand by an establishment selling rolls of camera film, the bags preferably having the name and address of such establishment or of an establishment which develops exposed films printed on the side of the bag as indicated at 10, and being furnished to the purchasers of the film. After a roll of film has been exposed, it may be mailed or otherwise sent by the purchaser to an establishment for development and the return of the negatives and prints therefrom by merely inserting the roll of exposed film, together with the proper amount of money, into the bag and closing and securing its mouth, inserting the name and return address of the purchaser in the form or space 13 provided therefor on the flap or extension 12 and folding this flap or extension against the adjacent side of the bag, and applying the proper postage to

the space 11 and depositing the bag in the mail. The bulged form of the bag, after a roll of film has been inserted therein, tends to hold the flap 12 against the adjacent side 2 of the bag, as shown in Fig. 3, thus avoiding its accidental detachment in the mail or while being handled, and as this flap extends from the side of the bag opposite to that which contains the address 10, it cannot swing into a position to obscure that address.

After the establishment to which the bag is addressed has received the bag and roll of film, the flap 12, which contains the name and address of the person to whom the negatives and prints are to be sent, is torn off along the line 16 or otherwise detached from the bag and may be stapled or otherwise attached to one end of the roll of film, thereby providing reliable means for identifying the sender thereof, and after development of the film, this flap may be detached therefrom and used to supply the return address of the sender, as for example, by affixing it to the usual envelope in which negatives and prints are mailed or otherwise delivered, as by applying adhesive to the back of the flap.

Bags according to the present invention thus greatly facilitate the mailing or sending of rolls of exposed films to establishments for developing and the returning of the negatives and prints, and they provide greater certainty in the return of the negatives and prints to the proper individuals. Since these bags may be manufactured on bag machines of usual and well known forms, they may be produced inexpensively.

I claim as my invention:

1. A mailing bag comprising a tubular body having opposed sides and pleats connecting their longitudinal edges, one of said sides providing an area for the address of an addressee and the other side having a longitudinal seam, and a return address flap formed by a lateral continuation of an edge of said longitudinal seam exteriorly beyond the respective side of the body and foldable against the latter side of the body, said flap being centrally positioned with respect to said longitudinal seam and extending over the major portion of the length of said seam.

2. A package for mailing comprising a bag containing an article to be mailed, said bag having a side bearing the address of an addressee and having an opposite side provided with a seam extending along one of its longitudinal edges, pleats connecting the longitudinal edges of said sides and expanded by said article, and closures holding the ends of the pleats in collapsed condition, the outer edge of said seam being extended exteriorly beyond said longitudinal edge to form a flap having a return address thereon, said flap being foldable to bring the return address thereon against the seam side of the bag, and being retained in such folded position by the collapsed ends and expanded intermediate portions of the pleats.

TRUE M. AVERY.
